UNITED STATES PATENT OFFICE

2,636,564

RIB TYPE CASING CENTRALIZER

Louis Kluck, Odessa, Tex.

Application February 1, 1952, Serial No. 269,441

1 Claim. (Cl. 166—4)

1

This invention relates to new and useful improvements in casing centralizers and the primary object of the present invention is to provide a casing centralizer having novel and improved features over that disclosed in my pending application Serial No. 140,677, filed January 26, 1950.

Another important object of the present invention is to provide a casing centralizer including a plurality of circumferentially spaced leaf springs having central bowed portions that will yieldingly engage the wall of a hole to retain a casing centered within the hole.

A further object of the present invention is to provide a casing centralizer of the aforementioned character that is quickly and readily applied about a casing to center the casing in a hole as the casing is permanently fixed in the hole by cement.

A still further aim of the present invention is to provide a rib type casing centralizer that is simple and practical in construction, strong and reliable in use, inexpensive to manufacture and install, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a sectional view of a well hole and showing a casing centered within the hole by the present invention;

Figure 2 is a perspective view of the present casing centralizer;

Figure 3 is an enlarged horizontal sectional view taken substantially on the plane of section line 3—3 of Figure 1; and,

Figure 4 is an enlarged horizontal sectional view taken substantially on the plane of section line 4—4 of Figure 1.

Referring now to the drawings in detail, wherein for the purpose of illustration, there is disclosed a preferred embodiment of the present invention, the numeral 10 comprises a cage member including upper and lower identical ring elements 12 and 14 that are connected by hollow, substantially channel-shaped, reinforcing and strengthening ribs 16.

The ribs 16 are spaced circumferentially about the ring elements and the upper and lower smoothly rounded, preferably convex, ends 18 of the ribs are fixed by welding to the outer peripheries of the ring elements.

The lower ends of a plurality of circumferentially spaced leaf springs 20 are fixed by welding to the outer periphery of the lower ring element

2

14 and the upper ends of the springs 20 are slidably received in circumferentially spaced channel-shaped guides 22 that are welded to the outer periphery of the upper ring element 12. Each of the springs 20 is provided with a central bowed portion or concavo-convex portion 24 and these portions project radially outwardly beyond the ring elements.

The leaf springs 20 alternate with the ribs 16 so that the cage member 10 will be uniformly strengthened. The ribs 16 will prevent the springs from breaking since they will restrict the amount of tension placed on the springs.

An abutment ring 24 is positioned on the casing C above the cage member 10 which is slipped on the casing above a joint J. Nuts 26 are welded to diametrically opposite sides of the ring 24 and oppose apertures 28 in the ring 24. Set screws 30 are threaded through the nuts and extend radially inwardly of the ring 24 to bite against the casing C and prevent shifting of the ring 24 on the casing.

As the casing is lowered into a well hole H the hump portions 24 will engage the wall of the hole to center the casing within the hole. The ribs 16 will also center the casing within the hole. Then cement is poured in the hole about the casing to anchor the casing within the hole.

Having described the invention, what is claimed as new is:

30 A casing centralizer comprising upper and lower ring elements, a plurality of circumferentially spaced hollow ribs terminally fixed to the outer peripheries of the ring elements and joining and strengthening the ring elements; a plurality of circumferentially spaced leaf springs having lower ends fixed to the outer periphery of the lower ring element and upper ends contacting the outer periphery of the upper ring element, said springs alternating with the ribs and having central bowed portions projecting outwardly beyond the ring elements, and a plurality of circumferentially spaced channel-shaped guides fixed to the outer periphery of the upper ring element and slidably receiving the upper ends of the springs.

LOUIS KLUCK.
